UNITED STATES PATENT OFFICE

153,833

DESIGN FOR A LAMP STAND

Eunice M. St. John, Los Angeles, Calif.

Application August 14, 1948, Serial No. 148,127

Term of patent 7 years

(Cl. D48—20)

To all whom it may concern:

Be it known that I, Eunice M. St. John, citizen of the United States, residing at 1153 Muirfield Road, in the county of Los Angeles and State of California, have invented a new, original, and ornamental Design for Lamp Stand, of which the following is a specification, reference being had to the accompanying drawing, forming part thereof.

Fig. 1 is a perspective view of a lamp stand, showing my new design; and

Fig. 2 is a side elevational view thereof.

I claim:

The ornamental design for a lamp stand, as shown.

EUNICE M. ST. JOHN.
